UNITED STATES PATENT OFFICE.

HARRY M. HILL, OF ST. LOUIS, MISSOURI.

ELECTRODE FOR WATER-HEATERS.

SPECIFICATION forming part of Letters Patent No. 678,782, dated July 16, 1901.

Application filed October 25, 1900. Serial No. 34,298. (No model.)

To all whom it may concern:

Be it known that I, HARRY M. HILL, a citizen of the United States, residing at the city of St. Louis, State of Missouri, have invented 5 a certain new and useful Improvement in Electrodes for Water-Heaters, of which the following is a full, clear, and exact description, such as will enable others skilled in the art to which it appertains to make and use 10 the same, reference being had to the accompanying drawings, forming part of this specification, in which—

Figure 1 is a vertical sectional view through a water-heater in which is arranged my improved electrode, and Fig. 2 is an enlarged detail view illustrating the zigzag passages formed by the electrodes for the water to be heated.

This invention relates to a new and useful 20 improvement in electrodes for water-heaters, the object being to so construct an electrode as to insure a long life thereof and to prevent the disintegrated particles of which the electrode is composed from passing off with the 25 water being heated.

With this object in view the invention consists in the construction, arrangement, and combination of the several parts, all as will hereinafter be described and afterward pointed 30 ed out in the claims.

In the accompanying drawings I have illustrated an electrical water-heater similar to that forming the subject-matter of an application filed by me on or about July 2, 1900, 35 serially numbered 22,339, which heater is provided with my improved electrode.

I will briefly describe the construction of the water-heater shown in the drawings.

1 indicates a supply-pipe for the water, and 40 2 a casting arranged thereon, which casting is preferably provided with a pipe 3, extending thereabove.

4 is a spider-ring formed on the casting for supporting the electrode 5, said electrode 45 forming the core of the heater. This electrode is provided with a central bore opening into the bottom of the base-casting, while the top of the electrode is closed. The pipe 3 terminates short of the top of the electrode, leaving 50 a suitable space for the passage of water. This electrode 5 is preferably made of carbon pressed into shape, its periphery being pref-

erably formed with spiral grooves in the shape of screw-threads, the faces of said threads being covered by some suitable fabric, (indicated at 6,) which is pressed into shape when the electrode is being formed, a wire or cord 7 being wound around in the bottom of the groove to hold the cloth or fabric in its designed position. However, the cloth 60 may be formed with a nap on one face, next the carbon, which nap when the green carbon is applied will form a permanent attachment for the cloth. The object in facing the carbon electrode with cloth or fabric is to prevent 65 the disintegrated particles of which the electrode is composed from passing out with the running water. The presence of the fabric enables the electrode to be molded much easier, and when molded the electrode will 70 hold its shape better than where the sharp corners of the green carbon are exposed. Where a wire or cord is used at the base of the threads, this, in addition to holding the fabric in position, also assists in preserving the shape 75 of the electrode. The electrode shown in the accompanying drawings is formed with a single thread; but it is obvious that a double thread may be formed at its base and, further, that these threads may be interrupted or the 80 projections shaped as desired. The purpose of these threads, as will presently be seen, is to cause the water passing through the heater to travel in other than a straight path, and this, as will be obvious, can be accomplished 85 in various ways, the formation of the thread, male and female, in the core-electrode and its encircling electrode being a convenient and advantageous way of doing this.

8 indicates a cylinder, preferably in the 90 form of a short section of pipe, which is threaded into the base-casting 2, and its top is closed by a cap 9. This cylinder 8 carries the encircling electrode 10, which electrode is insulated from its support for well-understood 95 reasons. I will state here that the core-electrode 5 is likewise insulated from its support where it is desired to use a metallic return-wire; but where the circuit is grounded the core-electrode 5 may be an electrical connection with the grounded water-supply pipe 1.

The electrode 10 is preferably formed with spiral grooves in its inner face, said grooves producing substantially a female thread

which, with the male thread on the core-electrode 5 when the parts are assembled, forms a zigzag path for the water. The inner face of electrode 10 is covered with fabric 11 for the same purpose as that attributed to the fabric 6 on the core-electrode 5; but instead of having a supporting wire or cord in the grooves in electrode 10 I prefer to introduce an angle-support 12, which conforms to the shape of the bottom of the groove.

In the manufacture of electrode 10 a mandrel is preferably employed, which mandrel is preferably grooved, as desired, and on the tops of the threads on the mandrel the supporting-angle 12 is arranged, a roller having a V-shaped groove being employed for this purpose. After the supporting-angle is arranged in position fabric in the form of a cylinder and of the proper length is introduced over the mandrel and the green or wet carbon placed in position, pressing the fabric in place in the grooves, after which pressure is applied, then the mandrel removed, and the electrode dried. The core-electrode 5 terminates short of the cap-piece 9 to form a chamber in the upper end of the heater from which leads a discharge-pipe 13, said discharge-pipe having a spigot 14 secured thereto. This spigot may be of the usual type, but is preferably so constructed that when the operating-handle is turned in either direction the spigot will be opened to permit the passage of water therethrough. I am thus enabled to run cold water through the apparatus when the spigot is turned in one direction, and when the spigot is turned in the opposite direction the circuit is completed and the electrodes energized, whereby the water passing through the apparatus will be heated before it issues from the spigot. I do not claim the construction of this spigot in this application, and therefore will not give a detailed description of the same here, I deeming it sufficient to state that the spigot acts as an electric switch to establish proper electrical connections with the electrodes; but it is obvious that these connections through the electrodes may be made in any other manner.

From the above it will be seen that water from pipe 1 will pass through pipe 3 and contact with the core 5 at or near its top. If the current is on, this core will be heated to some extent, and as the entering water passes downwardly throughout the length of the core it will become heated to some degree, this initial heating of the water being advantageous and not interfering with the operation of the apparatus in any way. As the water leaves the chamber in the core 5 it passes through the base-casting and thence travels upwardly in a zigzag path between the electrodes 5 and 10. As an electric current--say of one hundred and ten volts--will

destroy all animal and vegetable matter in water to a large extent, the zigzag path which the water being treated is compelled to travel is advantageous in that it tends to precipitate any foreign matter in the water in the grooves of either the core 5 or the encircling electrode 10. This precipitation is due to the formation of eddies in the bases of the grooves, which eddies retain the precipitated matter and prevent its escape through the spigot. The water passing upwardly through the zigzag path formed by the threads will also be given a whirling motion, so that when it reaches the chamber in the top of the heater centrifugal action will assist in ridding the water of such foreign particles which are affected thereby. The discharge-pipe 13 is therefore led from the center of this chamber, and in area this pipe is not only under pressure in the apparatus, but is compelled to move slowly. In fact, depending upon the size of the apparatus, the water can be held therein so long as to be treated almost in a static condition. I prefer, however, that the water be in motion while being treated in order that it may be deprived, as far as possible, of its impurities.

I am aware that minor changes in the construction, arrangement, and combination of my device can be made and substituted for those herein shown and described without in the least departing from the nature and principle of my invention.

Having thus described my invention, what I claim, and desire to secure by Letters Patent, is—

1. The combination with an electrode, of a fabric covering therefor whose nap is embedded in the electrode to serve as a binder for said covering; substantially as described.
2. An electrode formed with grooves in its face, and a fabric covering which is pressed into said grooves; substantially as described.
3. The combination with a cylindrical electrode formed with a spiral groove, of a fabric covering which is pressed into said grooves, and a support for said covering arranged in said grooves; substantially as described.
4. The combination with an electrode formed with a spiral groove in its inner face, of a fabric covering which is shaped to the contour of said groove, and a V-shaped support for said covering, said support being arranged in said groove; substantially as described.

In testimony whereof I hereunto affix my signature, in the presence of two witnesses, this 11th day of October, 1900.

HARRY M. HILL.
